UNITED STATES PATENT OFFICE.

JAY M. AXTELL AND FRED G. VON HOFEN, OF FORT WORTH, TEXAS.

GAS BURNER.

Application filed November 24, 1924. Serial No. 751,806.

To all whom it may concern:

Be it known that we, JAY M. AXTELL and FRED G. VON HOFEN, citizens of the United States, residing at Fort Worth, in the county 5 of Tarrant and State of Texas, have invented certain new and useful Improvements in Gas Burners, of which the following is a specification.

Our invention relates to gas burners and 10 more particularly to circulating gas burners; and the object is to provide gas burners which have a plurality of jets and to provide means for causing a circulation of the gas so that uniform pressure is maintained 15 for all the jets. The object is to provide gas burners for general heating purposes and particularly to burners in which the circulation of the gas will exert substantially the same pressure at all points in the burners 20 so that the burners will furnish heat of substantially the same temperature throughout the heated zone. Other objects and advantages will be fully explained in the following description and the invention will be 25 more particularly pointed out in the claims.

Reference is had to the accompanying drawings which form a part of this application.

Fig. 1 is a plan view of the improved 30 burner. Fig. 2 is a horizontal section of the same. Fig. 3 is a plan view of a burner which is a slight variation of the burner previously shown.

Similar characters of reference are used 35 to indicate the same parts throughout the several views.

The burner is preferably made of a single casting having a general quadrangular shape with a central member communicating 40 with the end members. The receiving end 1 is provided with a boss 2 into which is screwed a nozzle 3 for supplying gas to the burner. The outer end 4 of the nozzle is threaded interiorly to receive the end of 45 a supply pipe 5. The end member 1 has an interiorly projecting boss 6 which forms a socket for the inner end of the nozzle 3 and also as a gas directing means for the return currents of gas. Gas is fed through the nozzle 50 into a central member 7 which is connected with and communicates with the end member 8. The end member 8 is connected with and communicates with the side members 9 and 10 which also communicate with the end member 1. The members 1, 7, 8, 9, 55 and 10 all have passage for gas and may be

tubular in form. Openings 11 are made at the corners of the burner in line with the members 9 and 10 for convenience in the manufacture of the burners. These openings are to be closed with any suitable plugs. The burner is provided with any convenient or required number of burner nozzles 12 to be distributed according to the type of heater in which the burner is to be used. 60 65

In operation the gas enters the central member 7 and takes the direction of the arrow heads. At the closed end 8, the gas is divided for distribution and circulation through the lateral members 9 and 10. The 70 end member 8 is provided with an inwardly projecting divider 13 for dividing the gas. The gas, in passing through the conducting members 7, 8, 9, and 10 is fed to the nozzles 12. When the gas reaches the member 1 on 75 the return trip, it is deflected by the deflector 6 into the member 7. The gas in passing through the nozzle 3 tends to create a suction which draws the gas from the members 9 and 10 and drives the same through the 80 member 7. In this manner, the gas pressure is maintained substantially uniform in all the members 1, 7, 8, 9, and 10.

In the form of burner shown in Fig. 3, the lateral members 14 and 15 are substantially circular with no end members. At the side diametrically opposite the supply nozzle 4, a divider 16 serves to direct the passing gas into the members 14 and 15. The members 14 and 15 have inwardly projecting circulating members 17 which are provided with baffles 18. The gas will be compelled to take the direction of the arrow heads. The circulation of gas in this form of burner is similar to the circulation of 95 the gas in the form shown in Figs. 1 and 2.

What we claim, is,—

1. A gas burner comprising distributing members consisting of a central receiving member, end members connected therewith and communicating therewith and said end members having dividers, and lateral members communicating with said end members, and a receiving nozzle for directing gas through said central member, said distributing members having burner nozzles. 100 105

2. A gas burner comprising circulating members provided with burner nozzles and consisting of a central receiving member, a receiving end member provided with an inwardly projecting divider for directing gas to said central member, an end member con- 110

nected with said central member at the discharge end and provided with an inwardly projecting divider, and lateral members connected and communicating with said end members, and a supply nozzle for directing gas into said central member.

3. A gas burner comprising circulating members provided with burner nozzles and consisting of a central circulating member having a receiving end and a discharge end, lateral circulating members on opposite sides of said central member and connected with and communicating with both ends of said

central member, a divider deflector at the discharge end of said central member for directing gas into said lateral members, and a nozzle for supplying gas from the supply source to said central member and for aiding in directing gas from said lateral members into the receiving end of said central member.

In testimony whereof, we set our hands, this 19th day of November, 1924.

JAY M. AXTELL.
FRED G. VON HOFEN.
